UNITED STATES PATENT OFFICE.

CHESTER HORNE, OF TORONTO, CANADA, ASSIGNOR OF TWO-THIRDS TO
JOSEPH JONES DAVIES AND SAMUEL E. HORNE, OF SAME PLACE.

PRINTER'S GALLEY.

SPECIFICATION forming part of Letters Patent No. 465,931, dated December 29, 1891.

Application filed November 28, 1890. Serial No. 372,792. (No model.)

To all whom it may concern:

Be it known that I, CHESTER HORNE, printer, of the city of Toronto, in the county of York, in the Province of Ontario, Canada, have invented certain new and useful Improvements in Printers' Galleys, of which the following is a specification.

The object of the invention is, first, to design a galley of simple, cheap, and durable construction, and, secondly, to provide a simple and ready means for adjusting the side-stick of the galley, whereby the loose quoins now commonly in use are dispensed with.

Figure 1 is a perspective view showing the construction of my improved galley. Fig. 2 is a view of the main portion of the frame as stamped out. Fig. 3 is a view of the angle metal portion of the frame. Fig. 4 is a cross-section through *x y*, looking toward the closed end of the galley. Fig. 5 is a detail of the blocks.

In the drawings like letters indicate corresponding parts.

A is the main portion of the frame, which is bent at *a* and *b* (shown by dotted lines in Fig. 2) into the form shown by full lines in Fig. 1, the parts A' forming the sides, as indicated, and the portion B forming the one end, the other being preferably left open. The sides A' are riveted at the top to the sides C of the angle-plate, forming a skeleton frame, and the end B is riveted at the top to the end piece C' of the angle metal. The outer edge of the lower flange *c* of the angle metal butts at the sides and ends against the apex of the angle formed at *b*. The sides C and end C' are perpendicular to the bottom plate A. The ends *a' b'* are simply turned around the end B and riveted or otherwise secured to it.

D are blocks fastened to the side-stick.

E and F are blocks fastened to the adjusting-slide G, which is designed to move longitudinally in the groove *g*, formed by the bar H, which is secured to the bottom of the galley.

The blocks D have inclined sides *d*, with dovetail tongues *d'*, which fit into and move lengthwise within corresponding grooves *f'*, made in the adjacently-opposite inclined side *f* of the block F. It will be noticed that the adjacent sides *d* and *f* of the central blocks are not tongued and grooved, as in practice we find it cheaper and just as effective not to do

so, as they are really only necessary to stiffen the side-stick E.

55

I is a thumb-piece secured to the slide G.

J is an L-shaped piece secured to the side-stick E, the base lying flat against the bottom of the galley, and being only long enough to span the space between the side-stick E and that side of the galley when the side-stick is completely closed.

K is a strap against which the edge of the piece J butts, thus holding the side-stick in position during its lateral movement.

65

It will now be seen that in order to adjust the side-stick E laterally it is merely necessary to manipulate the thumb-piece I until the desired position of the side piece is obtained, when it will be securely locked.

70

In Fig. 1 I show the form more especially designed for a news-galley; but it will of course be understood that the side-stick and its locking attachment might be omitted if my galley is intended to be used as a job-galley. It will also be understood that the form of the tongue and groove in the blocks may be altered as long as it will not permit the blocks to draw apart.

From this description it will be seen that a cheap and effective galley is produced, as it is only in two pieces, which are put together without the use of screws, while the side-stick adjusting and locking device is extremely simple and readily manipulated.

85

What I claim as my invention is—

1. A printer's galley consisting of a skeleton frame having a vertical portion C and a base *c*, extending at right angles therefrom, and a plate or frame having its sides and end turned up around the base-plate to inclose the skeleton frame, the parts being secured together, substantially as described.

2. In a printer's galley, a side-stick having connected to it a set of blocks with inclined faces having dovetail tongues formed in the side to fit into corresponding grooves in a reversely-inclined side of the set of the blocks secured to the adjusting-slide, in combination with the grooved bar, L-shaped piece attached to the side-stick and stop, substantially as and for the purpose specified.

100
CHESTER HORNE.
